FEEDING FINGER

John Evasic, Detroit, Mich.

Application January 12, 1938, Serial No. 184,652

6 Claims. (Cl. 29—61)

My invention relates to a new and useful improvement in a feeding finger adapted for use for feeding elongated strips of metal into machines which are intended to perform work upon the strip of metal. In this type of mechanism the feeding finger is generally attached to a feeding tube, both of which are reciprocated by the operating machine to feed forwardly a predetermined length of the strip of material and then withdraw and move longitudinally of the material to obtain another grip. In the forward movement, the strip of material fed is gripped tightly and in the backward movement the strip is released to permit the feeding finger to obtain another grip. It commonly happens that when the strip of material has been fed forwardly its desired length, the movement of the feeding tube has not as yet been completed with the result that as the completion of this movement is effected, parts of the machine as well as the strip of metal and the feeding finger and tube, are placed under strain often resulting in distortion and sometimes in fracture or other damage to parts of the machine.

It is an object of the present invention to provide a feeding finger so arranged and constructed that while it will feed forwardly, the strip of metal under firm pressure, it will also, when this pressure extends beyond a predetermined pressure, permit a yielding of the parts connecting the feeding finger and the feeding tube to relieve the mechanism of undue strain.

It is another object of the invention to provide a floating connection between the feeding finger and the feeding tube so that when undue pressure is exerted between these two parts, a yielding of the connections may be effected.

Another object of the invention is the provision of a simple and effective gripping member in the feeding finger whereby the strip of metal to be fed may be firmly gripped on the forward stroke and easily and quickly released on the backward stroke.

Another object of the invention is the provision of a feeding finger so arranged and constructed that a minimum number of parts are utilized for effecting a firm grip.

Other objects will appear hereinafter.

The invention consists of the combination and arrangement of parts hereinafter described and claimed.

The invention will be best understood by a reference to the accompanying drawing which forms a part of this specification, and in which,

Fig. 1 is a side, elevational view of the invention.

Fig. 2 is a longitudinal, central, sectional view of the invention.

Fig. 3 is a fragmentary, sectional view slightly enlarged taken through the feeding finger.

Fig. 4 is a sectional view taken on line 4—4 of Fig. 3.

In the drawing I have illustrated the invention used with a feeding tube 9. Slidably connected to the rear end of this feeding tube, in telescopic relation therewith, is the hollow thrust delivery member 10, threaded through which is a set screw 11 riding in an axial slot 12 formed in the tube 9. This thrust delivery member 10 is connected to the operating part of the machine with which used and serves as a means for effecting a reciprocation of the tube 9. Positioned within the head and engaging at one end, the end of the tube 9 and at its opposite end the base of the thrust delivery member 10 is a coil spring 12' which serves to retain the head 10 thrust rearwardly of the tube 9. The base of the thrust delivery member 10 is formed with a central opening 13 through which the rod 14 of metal to be fitted extends. Inserted slideably in the forward end of the tube 9 is a feeding finger sleeve 15 which is prevented from being withdrawn from the tube 9 by means of the set screw 16. A spring 17 embraces the sleeve 15 and engages, at one end against the end of the tube 9 and at the opposite end against the face of the head 18 for normally retaining the sleeve 15 thrust outwardly of the tube 9. Threaded on the head 18 is a cover 19 which serves to retain in position the gripping mechanism located within the head. This gripping mechanism comprises a ring 20 having an opening formed therethrough of sufficient size to permit play when the rod 14 is projected therethrough. Extending axially of the ring 20, at one side thereof, is a flange or axial extension 21 which is provided with a peripherally projecting ball 22 to facilitate slideable movement of the ring 20 axially of the head 18. In this slideable movement the ball 22 engages against the inclined inner surface 25 of the head 18 so as to effect a rocking of the ring 20 axially and thereby clamp the ring 20 on the rod 14.

A spring 23 serves to engage the ring 20 and force it inwardly of the head 18 to normally maintain it in clamped position. This construction is such that as the head 18 is moved axially of the rod 14 to the left of the drawing, the ring 20 will be tilted so that its axis is inclined to

the axis of the rod 14 and thereby the rod 14 will be gripped by the ring 20 sufficiently to effect a feeding of the rod 14 in unison with the movement of the sleeve 15. When the rod 14 is held firm at one end and the head 18 is moved axially thereof to the right of the drawing, the ring 20 will release its grip and permit a free sliding of the head 18 longitudinally of the rod 14.

10 In the feeding movement the thrust is delivered from the head 10 through spring 12' to the tube 9 and from the tube 9 through the spring 17 to the head 18. There is thus a floating mounting in which yieldable parts are utilized for transmitting the feeding thrust. The springs 12' and 17 are of sufficient tension that these parts do not move relatively to each other in a normal operation but serve to present a sufficiently rigid structure for normal feeding 20 of the rod 14. However, should an undue obstruction be met so that abnormal resistance would be encountered, the springs 17 and 12' would permit the yielding of the parts sufficiently to prevent damage either to the feeding tube, 25 the feeding finger, or the connecting parts.

In this way I have constructed a feeding finger which is simple in structure and which is highly efficient in use and free from the objectionable features enumerated herein.

30 While I have illustrated and described the preferred form of construction I do not wish to limit myself to the precise details of structure shown but desire to avail myself of such variations and modifications as may come within the 35 scope of the appended claims.

What I claim as new is:

1. A feeding finger of the class described, comprising: a hollow thrust delivery member; a tubular member mounted in telescopic relation with 40 said delivery member; a head; a gripping mechanism in said head for gripping a workpiece projected therethrough; a sleeve projecting outwardly from said head and slideably insertible into said tubular member; a spring for resisting 45 slideable movement of said sleeve inwardly of said tubular member; and a spring in said thrust delivery member for resisting inward movement of said tubular member relatively to said thrust delivery member.

50 2. In a feeding finger of the class described, a cup-shaped head having a tapered inner surface; an annular member mounted in said head adapted for embracing a work-piece projected through said head; and an axially directed flange

on one side of said annular member engageable with said tapered surface for effecting a tilting of said annular member on the workpiece for clamping the same.

3. In a feeding finger of the class described, 5 a cup-shaped head having a tapered inner surface; an annular member mounted in said head adapted for embracing a workpiece projected through said head; an axially directed flange on one side of said annular member engageable with 10 said tapered surface for effecting a tilting of said annular member on the workpiece for clamping the same; and a spring in said head for moving said annular member into position for effecting the engagement of said flange with said tapered 15 surface.

4. In a feeding finger of the class described, a cup-shaped head having a tapered inner surface; an annular member mounted in said head adapted for embracing a workpiece projected through 20 said head; an axially directed flange on one side of said annular member engageable with said tapered surface for effecting a tilting of said annular member on the workpiece for clamping the same; a spring in said head for moving said annular member into position for effecting the engagement of said flange with said tapered 25 surface; and a rotatable member carried by said flange and engageable with said tapered surface for reducing friction between said tapered surface 30 and said flange.

5. In a feeding finger of the class described: a cup-shaped head; an annular member positioned in said head adapted for embracing a workpiece projected through said head; an axial extension on said annular member projecting outwardly from one face thereof; and means associated with said head engageable with said extension upon axial movement of said annular member for effecting a tilting of said annular 35 member on the workpiece for clamping the same. 40

6. In a feeding finger of the class described: a cup-shaped head; an annular member positioned in said head adapted for embracing a workpiece projected through said head; an axial extension 45 on said annular member projecting outwardly from one face thereof; means associated with said head engageable with said extension upon axial movement of said annular member for effecting a tilting of said annular member on the 50 workpiece for clamping the same; and resilient means engageable with said annular member for effecting axial movement thereof.

JOHN EVASIC.
